UNITED STATES PATENT OFFICE.

JOHN E. HANSON, OF ST. PAUL, MINNESOTA.

CARPET-BEATER.

1,347,949.

Specification of Letters Patent. Patented July 27, 1920.

Application filed October 10, 1918. Serial No. 257,611.

To all whom it may concern:

Be it known that I, JOHN E. HANSON, a citizen of the United States, and a resident of St. Paul, in the county of Ramsey 5 and State of Minnesota, have invented certain new and useful Improvements in Carpet-Beaters, of which the following is a specification.

This invention relates to carpet beaters, 10 and an object of the invention is to provide a carpet beater including a plurality of pivotally mounted beaters or beating members which are normally held in a carpet engaging position by spiral springs and to embody in the beater structure, means operable by the travel of the beater over a carpet to raise the beater out of engagement with the carpet and against the tension of said springs, for a limited time after which the 15 action of the raising means is released and the beaters are quickly brought into engagement with the carpet by the contracting action of the springs.

More specifically, the invention comprehends the provision of a carpet beater including a pair of supporting wheels and a crank shaft connecting the said wheels, which crank shaft is rotated through the medium of a plurality of gears one of which 20 meshes with teeth formed upon the inner periphery of the supporting wheels, to rotate the crank shaft in a uniform direction upon rotation of the supporting wheels in either a forward or backward direction and 25 which crank shaft engages the pivoted beaters for moving them against the tension of their operating springs.

Other objects of this invention will appear in the following detailed description, 30 taken in connection with the accompanying drawings, forming a part of this specification, and in which drawings:

Figure 1 is a rear elevation showing part in section of the improved carpet beater,

Fig. 2 is a vertical section through the beater taken on the line 2—2 of Fig. 1, and

Fig. 3 is a vertical section taken on the line 3—3 of Fig. 1.

Referring more particularly to the drawings, wherein like characters indicate like and corresponding parts, 1 indicates the handle of the improved carpet beater which is connected by means of arms 2 and 3 to plates 4 and 5 respectively. These plates 4 50 and 5 have the inner section 6 of the supporting wheels 7 and 8 rigidly connected

thereto. The inner sections 6 of the supporting wheels 7 and 8 are disk-shaped and have central hubs or collars 9 spun or otherwise suitably formed thereon and these hubs form bearings for the hub 10 of the outer portions 11 of the wheels 7 and 8, allowing the outer portions 11 of the wheel to rotate about these hubs 9. The outer portions 11 comprise disks having annular flanges 12 formed about their periphery, the free inner edges of which flanges engage the periphery of the inner disks 6. The plates 4 and 5 are pivotally connected near their lower ends as shown at 13 to the disks 6 to permit the plates to be swung upon these pivots, as indicated in dotted lines in Fig. 3 of the drawings for moving the gears 14 into engagement with the internal teeth 15 of the outer rotatable section 11 of the wheels 7 and 8 when the handle 1 is pushed forwardly. The gears 14 are rotatably carried by stub shafts 16 which are carried by the plates 4 and 5 respectively and they travel through arcuate slots 17 formed in the stationary inner disks 6 of the wheel structure. The gears 14 mesh with the gears 18 which are carried by stub shafts 19. These stub shafts 19 are also carried by the plates 4 and 5 respectively and travel 80 in slots 20 formed in the inner stationary plates or disks 6 of the wheel structures upon pivotal movement of the plates 4 and 5. Supporting arms 21 are connected to the stub shafts 19 and they carry at their upper ends, the end of a crank shaft 22. The crank shaft 22 travels in slots 23 formed in the stationary inner disks 6 of the wheels 7 and 8 during pivotal movement of the plates 4 and 5. The crank shaft 22 has 90 gears 24 mounted thereon which mesh with the gears 18. When the handle 1 is drawn rearwardly, for moving the carpet beater backwardly, the gears 18 will be moved into engagement with the internal teeth 15, and thus the crank shaft will be rotated in a uniform direction upon movement of the carpet beater in either a forward or backward direction and when the handle, and the plates 4 and 5 are locked in a neutral 95 position as shown in dot and dash lines in Fig. 3, both sets of the gears 14 and 18 will be held out of engagement with the teeth 15 and the beater may be propelled without rotating the crank shaft 22. The gears 14 and 18 and the plates 4 and 5 are held in a neutral position, by means of a lock or brace 100 105 110

26 which is pivotally carried by the inner disks 6 of the wheel 7 and rests in a notch 27 formed in the upper end of the plate 4.

During the rotation of the crank shaft 5 22, rollers 30 carried by the wrist portions thereof engage the upper surfaces of the short end 31 of the beaters 32, rocking these beaters upon their pivots. The beaters 32 are pivotally mounted by means of forming 10 coils 33 intermediate their ends, upon a rod 34 which extends from one disk 6 to the other and they have their outer ends flattened as shown at 35 for beating engagement with a carpet, rug or the like. Collars 36 are carried 15 by the beaters inwardly of their pivots, and contractile spiral springs 37 are connected to these collars and to the overhanging flange 38 of a guard plate 39. This guard plate 39 is attached, by means of suitable attaching means indicated at 40, to the 20 disks 6 and it is provided with slots indicated at 41 in which the inner charge operating end of the beaters 32 travel during their pivotal movement under depressing action 25 of the rim portion of the crank shaft 22 and upward movement under the contracting action of the springs 37. This upward movement of the operating end of the beater under contracting action of the springs 37 30 will cause the flattened beating end 35 thereof to be sharply forced downwardly into engagement with a carpet, rug or the like for beating the same.

Guide plates 43 are carried by the disks 35 6 and engage the outer surfaces of the plates 4 and 5 for holding these spaced plates properly spaced from the disks 6 and also for forming support for the plates during their pivotal movement.

40 Generically, the operation of the beater is as follows: When it is desired to beat a carpet, the brace 26 is lifted out of the notch 27, and when the beater is pushed forwardly, by a forward push upon the handle 1, it 45 rides upon the upper surface of the plate 4 until said plate is in its most forward position when said brace drops or can be manually pushed into a downward position out of locking engagement. Upon pushing the 50 handle 1 forward, the plates 4 and 5 will be rocked to move the gears 14 in meshing engagement with the teeth 15 of the rotary sections of the wheels 7 and 8, and thus the rotation of these sections of the wheels will be 55 imparted through the gears 14, 18 and 24 to the crank shaft 22. During the rotation of the crank shaft 22, the operating ends of the various pivotally mounted beaters will be successively engaged by the rollers 60 30 mounted upon the wrist of the crank shaft and depressed against the contracting action of the springs 37, raising the beating ends 35 thereof upwardly out of engagement with the carpet or rug and after the rollers 65 30 pass off the terminals of the operating

ends 31 of the beaters, the respective springs 37 will contract, operating the beaters upon their pivots and bringing the beating ends 35 thereof into engagement with the carpet, rug or the like with a sharp quick move 70 ment effectively beating the same.

Changes in details may be made without departing from the spirit of this invention, but;

I claim:

1. In a carpet beater, the combination, of a plurality of pivotally mounted beaters, having carpet engaging portions, contractile springs connected to said beaters and normally holding said carpet engaging portions 80 in a carpet engaging position, means operable by the movement of said beater to move said beating members against the contracting action of said springs whereby when the beating elements are released from engagement by said last named means, said springs will return them to their normal positions, and means for locking said first named means against operation to permit movement of said beater without transmitting movement to said beating element. 90

2. In a carpet beater, the combination, of a plurality of pivotally mounted beating elements, supporting wheels, a crank shaft, and means operatively connecting said supporting wheels through said crank shaft for rotating the crank shaft in a uniform direction upon rotation of said supporting wheels in either a forward or backward direction, and means for locking said motion transmitting means in a neutral position to permit rotation of said wheels without imparting rotation to said crank shaft. 95

3. In a carpet beater, the combination, of a plurality of pivotally mounted beating 105 elements, said elements having carpet engaging portions, contractile springs connected to said beating elements and normally retaining said engaging portions in engagement with the carpet, supporting wheels for 110 said beaters, a crank shaft, means operatively connecting said supporting wheels to said crank shaft for rotating the crank shaft to move said beating elements against the contracting action of said springs for raising the engaging portions out of a carpet engaging position, said springs adapted to return the beating elements to their normal positions after this engagement between the crank shaft, and beating elements, said motion transmitting means being arranged to transmit rotation of said supporting wheels in either a forward or backward direction to said crank shaft in a uniform direction, and means for locking said motion transmitting 115 means in an inoperative position whereby said wheels may be rotated without imparting rotation to said crank shaft. 125

4. In a carpet beater, the combination, of a plurality of pivotally mounted beating ele- 130

ments, a crank shaft for operating said beating elements, a pivoted plate and means mounted upon said pivoted plate for transmitting motion of the carpet beater in either 5 a forward or backward direction to the crank shaft in a uniform direction.

5. In a carpet beater, the combination of a frame, an operating wheel mounted upon said frame, and having an internal gear, a 10 plurality of pivotally mounted beating elements, a crank shaft for operating said beat-

ing elements, a series of three co-meshing gears, either end one of which may be brought into co-meshing relation with said internal gear, said crank shaft operatively 15 connected with one of the end gears of said series and means to alternately shift the end gears of said series into meshing relation with said internal gear upon forward and reverse movement of said operating 20 wheel.

JOHN E. HANSON.
